(57) **CLAIM**

The ornamental design for a portable electric light source, as shown and described.

DESCRIPTION

FIG. 1 is a top plan view of a portable electric light source according to the present invention.

FIG. 2 is a left side elevational view of the portable electric light source.

FIG. 3 is a front elevational view of the portable electric light source.

FIG. 4 is a right side elevational view of the portable electric light source.

FIG. 5 is a rear elevational view of the portable electric light source; and,

FIG. 6 is a bottom plan view of the portable electric light source.
